TOY AIRPLANE

Frederick A. Christiansen, Los Angeles, Calif., assignor to W. H. Hammer and L. Rhodes, Los Angeles, Calif.

Application February 10, 1936, Serial No. 63,244

11 Claims. (Cl. 272—31)

The present invention relates to improvements of the apparatus shown and described in my co-pending application entitled Toy airplane, Serial No. 48,151, filed November 4, 1935.

5 An object of the invention is to provide an improved and simplified mechanism which includes a power take-off from the motor and in the clutch mechanism connected to be driven by said power take-off.

10 Another object of the invention is to provide a limited sliding means for the vertical tube or sleeve which is located above the driving means.

Another object of the invention is to provide an improvement over the construction disclosed 15 in my prior application of the power take-off mechanism including the clutch drive, such that this mechanism will be simplified and not as liable to require repairs.

Still another object is to provide a motor driving means for the plane located at the top of the column, and supported by the cap which surrounds the column.

20 A further object of the invention is to provide a control resembling the joy stick, or control stick of an airplane, whereby the speed of the airplane is regulated, as well as other movements of the plane, such as the looping, elevation, and the inclination of the plane both during take-off and the landing, may be controlled 25 in much the same manner as in a full sized commercial or privately owned plane.

Another object is to provide a means operating to prevent buckling of the spring which drives the outside tube.

30 An additional object of the invention is to provide improved counter-balancing mechanism for the plane while in flight, and particularly during the take-off and landing operations.

Another object is to improve the counter-balancing mechanism of the plane and its supporting 35 means.

The present application further includes improvements in the construction of the plane itself in order to provide for the use of a number of 40 different types of planes, and to allow these planes to be quickly mounted upon and detached from the supporting rod or tube which encloses the drive for the propeller without removal of the propeller from its driving shaft.

50 Other objects and advantages will appear hereinafter throughout the specification.

In the drawings:—

Figure 1 is a perspective view showing the entire assembly, the plane being shown in full lines 55 at one elevation and in dotted lines at another elevation;

Figure 2 is a vertical section through approximately the center of the pylon, with certain 60 parts shown in full lines;

Figure 3 is a reduced vertical section taken at right angles from that of Figure 2;

Figure 4 is a plan view of the flexible drive, showing the counter-balancing mechanism;

Figure 5 is a horizontal section taken on the 5 line 5—5 of Figure 3;

Figure 6 is a longitudinal vertical section of a typical airplane, forming a part of the present invention;

Figure 7 is a vertical section taken on the line 10 7—7 of Figure 6;

Figure 8 is a view of the control mechanism with one of the parts in full lines, and the remainder of them shown in vertical section;

Figure 9 is a detail view partly in vertical section, of the base of the pylon showing the control 15 lead-ins;

Figure 10 is a side elevation of the control wires and the runway plate, taken on the line 20 10—10 of Figure 1;

Figure 11 is a transverse section of the parts indicated in Figure 10, and

Figure 12 is a detail showing the construction 25 of the inner driving wire which drives the propeller of the plane from power furnished by the motor.

While the invention disclosed in my prior application above noted is quite suitable for most purposes as a toy, it has been found that some 30 of the mechanism disclosed in said application is apt to show wear after a considerable amount of hard usage, such as is usually given toys of this character by children, and the improvements described and claimed herein are directed to a toy which will withstand practically any amount 35 of hard usage without requiring repair or replacement of the parts of the mechanism or its controls.

Referring to the drawings, the numeral 1 indicates a pylon or column which may house the motor and many of the parts, including the power take-off mechanism, clutch parts, etc. The numeral 2 indicates a cap mounted on the top of the column, preferably square in outline, and having along two of its bottom sides, rails 3 45 which fit closely adjacent two of the square sides of the pylon to prevent rotation of the cap during the time the airplane is describing a circular course about the pylon. The rails 3 are attached to the base 4 of the cap, which base supports, for the purpose of convenient removal, the electric motor and many of the parts driven thereby. Supported by the under side of the base 4 by means of bolts or screws 4a, is a framework 5 to which is attached an 55 electric motor 6 having a shaft 7, which drives a worm 8, and a flexible wire shaft 9. The shaft 9 may be similar in construction to the shaft 12 shown in Figure 12. Said wire shaft 9 drives the propeller 10 by means of a coiled 60

spring drive 11 which is connected to drive the wire shaft 12 that is directly connected to the airplane propeller, as indicated in Figure 6 of the drawings. Surrounding these shafts and 5 spring drive, are the tubes 13 and 14, respectively, and the coil spring drive 15.

As will be noted from an inspection of Figure 1, the tube 14 is straight for the greater part of its length, but performs a curve as it approaches the airplane 16, and enters the plane 10 at about the longitudinal center thereof. The bottom portion as shown, or the side portion of the plane, is open so that the plane may be quickly mounted upon or removed from the 15 end of the tube 14. Preferably, the propeller is unconnected directly with the plane. While it is the purpose of this invention to provide an airplane which may be quickly removed and another plane substituted therefor, the propeller 20 preferably is intended to remain in fixed position on the end of the wire drive 12, and the plane may be removed from its mounting without necessitating the removal of the propeller, as was necessary by the construction 25 shown in my prior application.

Fixedly mounted on the tube 14 are a plurality of spaced collars 17. Mounted within the fuselage of the plane are a plurality of spring clips 18 so spaced as to grasp or clutch the tube 30 14 on the outside of each column, although of course it will be appreciated that the same effect would be obtained by having these clips so mounted as to grasp the tube inside of said collars 17. The clips are so placed as to mount 35 the plane below the center of gravity of the supporting rod 14. The plane is provided with struts 19 which support ground-engaging wheels 20 and a tail 21. There may be also a spring support 22 for the rear of the plane, as 40 shown in Figure 6.

Referring to the worm 8, it will be noted that said worm is in meshed relation with the worm wheel 23 mounted on the shaft 24. This shaft drives stub axles 25 and 26 by means of universal connections 27 and 28, such as ball and socket universal joints. Mounted on the ends of the stub axles 25 and 26 are drive wheels 29 and 30, either one of which may be brought into engagement with the drive disk 31 which is keyed to the tube 13. The drive wheels 45 preferably are provided with rubber driving rim portions or tires. As long as the motor 6 is running the two wheels 29 and 30 are also being driven by the power take-off represented by the worm drive axle 24 and the stub axles 25 and 26. At the will of the operator, however, either one of these wheels may be brought into engagement, by mechanism hereinafter to be described, with the driving disk 31, and it will be noted that upon engagement of the drive 50 wheel 29, said disk will be driven in one direction, and upon engagement with the driving wheel 30, said disk will be driven in the opposite direction. The disk drives the tube 13, and through the coil spring drive 15, the tube 14, 55 upon which the airplane is mounted. It will be noted, therefore, that the airplane may be rotated in either direction upon a transverse axis by engagement of either of the drive wheels 29 or 30, according to which is brought into engagement with the disk 31. Moreover, the tube 14 acts at all times as a bearing to allow the plane to automatically bank when the plane reaches a certain speed.

The numeral 32 indicates a U-shaped rock-

able frame, the ends of which are provided with holes for supporting the wheels 29 and 30, and one end of the stub axles 25 and 26. The frame 32 is pivotally mounted at about its center on frame 5 by means of pivot 33. This U frame 5 and the wheels are moved by a control means so that one or the other of the wheels engage the driving disk, by means of a link 34, which is pivotally attached to the U frame at 35, and which may be moved upwardly or downwardly 10 to cause either of said wheels to make contact with the disk 31.

The frame 5 has a horizontal portion having holes through which the bolts 4a extend. This horizontal portion has attached thereto, or preferably has integral therewith, a stationary sleeve 36, which forms a bearing for a supporting member 37, having upper and lower contacting and bearing portions 38 and 39. This member 37, as well as the outer decorative sleeve 40 20 seat in a rotary cup-shaped member 41, which is supported by the base 4, and which rotates upon the stationary sleeve 36. Said bearing member 37 is provided with a journal bearing 42 in which is pivotally mounted one end 43 of 25 a curved supporting arm 44, whose other end is rigidly attached to a sleeve 45, which slides freely on the tube 14 as the tube is raised or lowered, according to the altitude of the plane. Rigidly mounted on the supporting member 37 30 is an arm 46 having a plurality of holes 47, in any one of which one end of the spring 48 may be inserted for purposes of adjustment. The opposite end of the spring is connected to the sleeve 45 at the point 49. The outer sleeve 35 40 is provided with a notched end 50 so as to allow the coil spring drive 15 and parts 37 and arm 44, to move up and down without hindrance. This is facilitated by the fact that the bearings 38 and 39 slide on the rod 13, as well as 40 the cup-shaped member 41.

The lower end of the link 34 is connected to a bell crank lever 51 which is connected to one end of a push-wire 52, whose opposite end is pivotally connected at 53 to the joy stick 54. 45 Said joy stick is pivoted at 55 to a base 56. As will be noted from an inspection of Figure 8, the joy stick is maintained ordinarily in a vertical position by means of a pair of springs 57 which are so attached as to exert tension in opposite directions. The interior of the joy stick is preferably made hollow, and contains a coil 58 similarly acting as a rheostat. A movable plunger member 59 may be actuated by the thumb so as to force the same downwardly 55 against the tension of a spring 60, which ordinarily maintains the plunger 59 in the position as shown in Figure 8. When the plunger is forced downwardly, however, the coils of the rheostat are shorted, whereby to increase the 60 speed of the motor, and through the motor drive, the R. P. M. of the propeller, which moves the plane around the pylon, thereby increasing the speed of the plane as it travels around the pylon.

The lead-in wires from a suitable plug, not shown, are indicated by the numeral 61, which connect to the rheostat 58, the outgoing wires 62 being housed with the push-wire 52 in an armored cable 63, rigidly attached by solder or other means to the base 56. Attached to the 70 runway plate 64 are a plurality of spring clips 65 by which the runway plate may be attached at a suitable point to the cable 63, so as to allow the plane while travelling over a supporting sur-

face to run over the runway plate and not be stopped by the cable.

With the parts in the position indicated in Figure 1, a suitable switch, not shown, is actuated to complete the circuit, thus establishing the flow of current through the electrical connections above mentioned, or current may be caused to flow through these connections by merely attaching the plug, not shown, on the 10 end of wire 61 into a plug socket leading to a source of current. The current will then flow through the wires 61 into the rheostat 58, and out of the base 56 through wires 62 to the motor 6. Rotation of the motor shaft 1 will drive the 15 worm wheel 8, and through the connections mentioned, the two drive wheels 29 and 30, but these wheels will not drive the disk 31 with the joy stick in the vertical position, as shown in Figure 8. The motor shaft additionally drives the flexible wire shaft 9, and through the spring drive 11 and wire shaft 12 the propeller 10 is driven. By means of the tube 13, coil spring drive 15, and tube 14, the plane is caused to turn on a substantially transverse horizontal axis when either 20 25 of the wheels 29 or 30 have been moved into engagement with the driving disk 31, and this being accomplished by movement of the joy stick which actuates the link 34 to rock the U frame 32 which supports the wheels 29 and 30, so that 30 either of them may, at the will of the operator, drive the disk 31.

The operation is as follows: Assuming the plane is on the ground as indicated in dotted lines at Figure 1, and that current is flowing 35 to the motor 6, the plane starts to travel over the surface upon which it rests about the center point defined by the pylon 1. As the speed of the plane is increased, by means of the shortening of the coils of the rheostat, the stick 54 is 40 moved about the pivot 55 so as to cause one of the wheels 29 or 30 to engage the disk 31 in such manner as to result in the slight counter-clockwise rotation of the plane about its horizontal axis. The joy stick is brought to its neutral or vertical position when the nose of the 45 plane is headed slightly upwardly. After the plane has reached sufficient speed it will then leave the ground and rise from its supporting surface and fly around the pylon, its altitude depending upon the R. P. M. of the propeller, and the point at which it is "leveled off" by bringing the joy stick to its neutral position. The 50 plane may now be put through its paces by actuation of the stick 54 to cause looping or spiralling and practically any other one of the other stunts, which a real plane may be put through. At any time the plane may be caused to land by decreasing its speed and nosing down, by operating the stick in the opposite direction 55 from that which caused the plane to head upwardly or seek altitude, all of which operations may be controlled through the stick 54, in a manner quite similar to the method now employed in controlling a full sized commercial or privately owned plane. It will be seen that the 60 entire construction of the plane and its operating mechanism is rugged and substantially fool-proof in operation. There are no parts which are liable to require repair even after long use, 65 and the control means is accurate in its operation so as to faithfully simulate the actual flying of a real plane, whilst taking off, landing, cruising, or when stunting.

The drive spring 15 and the inner drive spring 75 75 are prevented from buckling by the curved

arm 44 which follows closely the general curvature of said springs, and thus prevents them from moving too far to that side on which the arm is located. The arm 44 is prevented from moving too far upwardly by the engagement of the 5 curved portion of the arm, adjacent the bearing 42, with a stop 65 affixed to the upper side of the supporting member 37. The plane supporting tube and the plane cannot therefore move in such a position that the rod 14 approaches a vertical position as the stop 65 prevents upward movement of the rod and plane at a point preferably slightly beyond that shown in Figure 1.

The counter-balancing means including the 15 parts 37, 42, 43, 45, 46, 47 and 48, as will be seen, are all mounted for limited movements on the tube 14 and stationary sleeve 36, so that the tension tending to lift the plane is changed for different positions of the plane in order to counter-balance the plane properly in its different 20 25 positions. Instead of having the plane with a cut-out bottom portion to allow quick removal of the plane from the tube 14, the side of the plane may be provided with a cut-out portion 25 and the clips 18 may be affixed to the opposite side of the inside portion of the plane, the clips are always preferably placed so that the center of gravity is below the tube 14. It will be further noted that the straight portion of the tube 30 is at or nearly at the longitudinal center of the plane and behind the airfoil of the plane to insure stability and balance to the plane.

The braided drive wire 12, as shown by Figure 12, adds life to the propeller drive. The wire 35 drive 9 which is attached to the motor shaft, is preferably also made of braided wire.

The foregoing description and the drawings are understood to be for illustrative purposes only, the drawings and specification herewith being used for illustrative purposes only, and it is further understood that the invention is capable of various modifications. I desire to be limited therefore in the practice of my invention only to the extent as defined by the appended claims. 45

What I claim is:—

1. A toy airplane apparatus comprising a toy plane and propeller, means for supporting and guiding the plane around a center, means for driving said plane by said propeller including a motor, and manually controlled means including a plurality of drive wheels and a drive disk for turning the plane about its supporting means so as to permit different angles of flight and maneuvers, said manually controlled means including additional means for selectively engaging or disengaging any one of said drive wheels with said drive disk. 50 55

2. A toy airplane apparatus comprising a toy plane and a propeller, means for supporting and guiding the plane around a center, means for driving said plane including a motor, and manually controlled means for turning the plane about its supporting means so as to permit different angles of flight and maneuvers, said manually controlled means including; a power drive means driven from said plane driving means, a U frame, wheels mounted in said U frame, stub axles for mounting said wheels, said axles having their bearing in said U frame, a driving connection to said stub axles from said power drive means, universal connections for said stub axles and a disk adapted to be driven or not driven by either of said wheels according to the position said U frame has been moved by said manual 70 75 75

control means to thereby cause turning of the plane to permit different angles of flight and maneuvers.

3. A toy airplane apparatus comprising a toy plane and a propeller, a standard, a cap non-rotatably mounted on said standard, a motor supported by said cap, a flexible drive shaft extending from the motor to the propeller of the toy airplane, a hollow supporting tube enclosing the flexible drive means and supporting the toy airplane from said standard, and manually controlled means for turning said tube for varying the angle of flight of said plane.

4. A toy airplane apparatus comprising a toy plane and a propeller, a standard, a flexible drive shaft extending from said standard to the propeller of the toy airplane, a hollow supporting tube enclosing the flexible drive and supporting the toy airplane from said standard, a motor for driving said flexible drive shaft and manually controlled means for causing said motor to rotate said tube for varying the angle of flight of said plane, said last named means including a driving disk rigidly attached to said tube, and a pair of continuously driven wheels, one being adapted to drive said disk in one direction and the other being adapted to drive said disk in the opposite direction and manual control means for moving either of said wheels into driving engagement with said disk whereby said plane may be turned in opposite directions.

5. A toy airplane apparatus comprising a plane having a propeller, a tubular plane supporting means, a flexible drive shaft extending through said means and connected to the propeller, motor means for turning said tube means in either direction to vary the angle of flight of said plane when mounted on said plane supporting means, clutch means for connecting said motor means to said tube means and a joy stick for actuating said clutch means, said stick having biasing means for holding the same in a neutral position whereby said clutch means is normally held in its unclutched position, to thereby allow said plane to maintain an adjusted position of flight.

6. A toy airplane apparatus comprising a plane having a propeller, a tubular plane supporting means, a plane adapted to be supported thereon, a flexible drive shaft extending through said means and connected to the propeller, motor means for turning said tube means in either direction to vary the angle of flight, clutch means for connecting the motor means to the tube means and for rotating said tube in either direction, and a joy stick having means for normally maintaining said clutch in inoperative position, a rheostat in said joy stick for controlling the speed of said motor means and propeller, pivotal mounting means for said stick whereby said stick may be moved in either direction to operate said clutch to rotate said tube in either direction whereby to cause rotation of said plane in either direction about a substantially horizontal axis.

7. A toy airplane apparatus having a tubular plane supporting means, a plane adapted to be supported thereon, a standard for supporting said tubular plane supporting means, a flexible drive shaft within said tubular supporting means, a propeller driven by said flexible drive shaft, motor means for driving said flexible drive shaft

and propeller, manually controlled means for rotating said tubular plane supporting means including a plurality of drive wheels continuously driven by said motor means, and means mounted on said tubular plane supporting means adapted to be driven by either of said drive wheels.

8. A toy airplane apparatus comprising a toy plane and propeller, a standard, a flexible drive shaft from said standard to the propeller of the toy airplane, a hollow supporting tube means enclosing the flexible drive and supporting the toy airplane from said standard, a motor for driving said flexible drive shaft and for turning said hollow supporting tube means, a cap non-rotatably mounted on said standard, a stationary sleeve extending through said cap, and a counter-balancing means for said toy plane turnably mounted on said sleeve and having sliding movement thereon, and rotatable means supported by said cap member, whereby said plane may rotate about said stationary sleeve as an axis to cause said plane to assume various angles of flight and maneuvers.

9. A toy airplane apparatus comprising a toy plane and propeller, a standard, a flexible drive shaft extending from the standard to the propeller, a hollow supporting tube enclosing the flexible drive means and supporting the toy plane from said standard, motor means for driving said flexible drive means, manually controlled means for rotating the plane on its transverse axis consisting of means for turning said tube comprising a driven means at one end thereof, a pivoted frame, two drive wheels supported by said frame, and drive means extending from said motor means to said drive wheels for continuously driving said wheels, said driven means being adapted to be engaged by either of said drive wheels or neither of them.

10. A toy airplane apparatus comprising a toy plane having a slot therein, a propeller, a tubular plane supporting member having one of its ends extending longitudinally of the plane when positioned thereon through said slot, a flexible drive shaft extending through said member and connected to the propeller, motor means for driving said flexible shaft and for turning said tubular member in either direction to vary the angle of flight of the plane, attaching means for removably mounting said plane on said member, said member acting as a bearing for said plane attaching means during flight to thus permit the plane to pivot about its longitudinal axis, and manually actuated means for connecting the motor means to said member and for disconnecting said motor means from said member.

11. A toy airplane apparatus comprising a toy plane having a slot therein, a propeller, a tubular plane supporting member having one of its ends extending longitudinally of the plane, when positioned thereon through said slot, a flexible drive shaft extending through said member and connected to the propeller, motor means for driving said flexible shaft and for turning said tubular member in either direction to vary the angle of flight of the plane, and a plurality of spring clips attached to said plane and adapted to hold said plane on said tubular supporting member and permit a limited turning movement on the longitudinal axis of said plane thereon.

FREDERICK A. CHRISTIANSEN.
